SCORE PAD DISPLAYING AND SUPPORTING
DEVICE FOR CARD TABLES

Lucien A. Marsh, San Francisco, Calif.

Application April 22, 1930. Serial No. 446,227

6 Claims. (Cl. 273—136)

This invention relates to game tables and especially to a card table adapted for use in playing contract bridge and similar games wherein a written record of the score is required.

5 In playing certain games, and especially contract bridge which requires the keeping of a written record of the score, from one to four score pads and pencils are usually employed and placed loosely on the table so that they may 10 frequently be referred to by each of the players. Where but one or two score pads are used by the four players the pads have to be frequently passed around for reference by the players which is a source of considerable inconvenience and annoyance to the players and causes interruptions 15 in the game, besides littering up the table with score pads and pencils.

The object of the present invention is primarily to leave the card table clear for the playing of the cards, absolutely unobstructed by score cards or pencils during the game and to eliminate interruption, annoyance and inconvenience to players as above stated by providing a card table having a view opening formed centrally thereon through which the score pad may be displayed; to provide a card table having a glass covered view opening so that the entire table surface may be utilized when playing; to provide a shelf or similar support from which the score pad may be readily removed when a new score is to be added and upon which the score pad may be quickly placed when the score is to be displayed; and further, to provide means whereby the shelf together with the score pad placed thereon may be readily rotated or positioned by any player so as to bring the written score into the most convenient position for reading.

40 The card table is shown by way of illustration in the accompanying drawing, in which—

Fig. 1 is a plan view which is partially broken away to disclose the structure of the table.

Fig. 2 is a vertical cross section taken on line II—II of Fig. 1, and

Fig. 3 is a perspective view of the shelf.

The table shown in the present instance employs an ordinary table top such as indicated at 4 which is covered with felt 5, or any similar suitable material, and it is supported by four 50 legs such as indicated at 6 which may be rigid or of the folding type as desired. Tables of this character are usually square and are generally employed for playing bridge or like card games.

In playing certain kinds of bridge such as contract bridge it is essential to keep a written score

as the game progresses and to place the score in such a position that it may be continuously referred to by the several players. In the present instance a square opening such as indicated at 7 is formed in the center of the table and this opening is covered with glass 8 or any other similar material so as to leave a plain unobstructed table surface for the reception of the cards during the playing of the game. Disposed below the opening 7 or the glass 8 is a shelf or like supporting device generally indicated at 9, this shelf being provided as a support for the score pad so that this may be referred to as often as desired by the several players.

If a stationary shelf is provided it is obvious that the written matter on the score pad could only be read by one person as the written matter would be upside down to the opposed players and could only be read with difficulty by those sitting at opposite sides. A feature of the present invention is to provide a shelf which may be rotated by anyone of the players so that the written matter may be moved into the most convenient position for reading. This is accomplished as follows:

The shelf indicated at 9 is in this instance provided with flanges such as indicated at 11 and these are bolted to a flat ring 12 which is turnably mounted between ring-shaped flanges indicated at 13 and 14. These flanges are spaced apart by a spacing ring so as to permit ring 12 which carries the shelf to be freely rotated and the spacing ring together with the rings 13 and 14 are secured to the underside of the table surface in any suitable manner or as here shown by screws 17. A ring 15 constructed of wire or like material and provided with spokes 16 is riveted or otherwise secured to the bottom portion of shelf 9 and this ring is of such a diameter that it may be grasped by any one of the players and rotated so as to bring the score pad into a position where it may be most conveniently read. In this manner the score pad is always maintained within convenient view of all players and it may be directly referred to by any player by merely rotating the shelf and score pad into reading position, hence no player is annoyed or interrupted by passing of the pad from one to the other and furthermore the pad is kept away from the table surface. Hence it is not in the way of anyone 105 nor can it be knocked off the table.

It will also be noted that the shelf is provided with a flaring mouth such as indicated at 10. This is also important as it permits the score keeper to readily remove the pad whenever a 110

new score is to be added and it also permits the score keeper to readily replace the pad in correct position on the shelf. It will be understood that the width and length of the shelf is approximately the same as the size of the pad so that it will always align with the shelf and assume the correct position with relation to the display opening 8 when placed on the shelf.

While certain features of the present invention 10 are more or less specifically described, I wish it understood that various changes may be resorted to within the scope of the appended claims. Similarly, that the materials and finishes of the several parts employed may be such as the manufacturer may decide, or varying conditions or 15 uses may demand.

Having thus described my invention, what I claim and desire to secure by Letters Patent is—

1. A card table having a table top with a display opening formed therein, a shelf attached to the lower surface of the table top in close proximity thereto and below the display opening, a pair of side members and an end section enclosing the shelf, and a flaring enlarged mouth 20 formed at the opposite end of the shelf to permit ready insertion or removal of a score pad.

2. A card table having a table top with a display opening formed therein, a shelf disposed below the display opening in close proximity to the lower surface of the table, and a rotary support securing the shelf with relation to the lower 25 surface of the table top.

3. A card table having a table top with a display opening formed therein, a shelf attached to the lower surface of the table top in close prox- 30

imity thereto and below the display opening, a pair of side members and an end section enclosing the shelf, and a flaring enlarged mouth formed at the opposite end of the shelf to permit ready insertion or removal of a score pad, said shelf being rotatably mounted with relation to the table top and the display opening. 80

4. A card table having a table top with a display opening formed therein, a shelf disposed below the display opening, a ring secured to the shelf, an annular bearing ring secured to the lower surface of the table top and forming a journal for the ring to which the shelf is secured and permitting rotation of the shelf and the ring supporting the same, and means for rotating the 85 shelf. 90

5. A card table having a table top with a display opening formed therein, a shelf disposed below the display opening, a ring secured to the shelf, an annular bearing ring secured to the 95 lower surface of the table top and forming a journal for the ring to which the shelf is secured and permitting rotation of the shelf and the ring supporting the same, and means for rotating the shelf, said means comprising a ring secured to the 100 shelf and being of such a diameter as to be readily reached from any side of the table so that it may be grasped to rotate the shelf.

6. The combination with a card table having an opening formed centrally of its top, of a trans- 105 parent covering for said opening, and a rotatable support for a score card directly beneath said opening.
